UNITED STATES PATENT OFFICE.

GERARDUS JACOBUS VAN SWAAY, OF DELFT, AND HENRI ISÄAC KEUS, OF HENGELO,
NETHERLANDS.

MAXIMUM CUT-OUT.

1,230,955.

Specification of Letters Patent. Patented June 26, 1917.

Application filed March 8, 1915. Serial No. 13,014.

To all whom it may concern:

Be it known that we, Professor GERARDUS JACOBUS VAN SWAAY, civil engineer, residing at Delft, Holland, and HENRI ISÄAC KEUS, electrical engineer, residing at Hengelo, Netherlands, subjects of the Queen of the Netherlands, have invented a certain new and useful Improvement in and Relating to a Maximum Cut-Out, of which the following is a specification.

This invention relates to switches which may be switched in and out by hand and which are further thrown out automatically on the current exceeding a predetermined value.

This principle is known and is for instance brought into practice in many oil switches in which an electro-mechanical relay is provided acting on an armature directly or indirectly connected to the releasing device generally consisting of a pawl. This armature when being attracted, on the current in the relay exceeding a certain limit, releases the pawl, so causing the switch to be thrown out by means of a spring or weight, without the operating member being returned thereby to its original "out" position, so that the automatic cut-out can not be influenced by holding the operating member.

The object of the present invention consists in the provision of a rotary maximum cut-out switch of compact form as for instance the shape of the well-known rotary light switches, in which all these properties are embodied and which is so constructed that it may be used as both hand operated switch and current limiting device in dwellings and the like in substitution of the usual installation consisting of a separate switch, a current limiting device and a fuse.

An important feature of the present invention consists in the provision of a coupling, adapted to connect the operating member to the bridging member which coupling engages the latter by means of an electro-magnetically actuated pawl only in the direction of closing the switch and during a part of or the whole angle across which the coupling is turned.

By this arrangement it is firstly rendered possible to turn the coupling backwardly without influencing the position of the bridging member, while lifting of the pawl suffices to make the bridging member entirely independent of the other parts of the

device, and secondly to render the position of the operating member before the switch is closed independent of the "in" and "out" positions of the bridging member, in other words which ever may be the position of the operating member before the switch is closed the bridging member will only be coupled to the operating member over the distance necessary to turn the bridging member from the "out" into the "in" position.

A second feature of the invention consists in the arrangement whereby only the bridging member is directly exposed to the tension of the quick-break spring while during the closing operation and after the switch is closed this tension is transmitted to the coupling through the bridging member itself and the electromagnetically actuated pawl and opposes the moving of the operating member in the direction of the "in" position. When lifting the pawl therefore only the bridging member is caused to move into the "out" position, while the means for keeping the coupling and the operating member in the "in" position also serves to keep the bridging member in this position.

A third feature consists in an arrangement by means of which the bridging member on being closed is only arrested in one direction by means of a fixed stop, while the coupling is in this position only arrested in the opposite direction by means of a pawl. The advantage of this arrangement lies in the fact that after the switch has been thrown out it is at the same moment ready for being closed without necessitating the operating member being turned back to the original position and without necessitating a second arresting device being moved out of action.

A fourth feature is formed firstly by a special device between the operating member and the body of the coupling, consisting of a carrier fixed to the operating member and stops on the coupling-body which are engaged by the carrier only in the direction of the switching-in movement and secondly by a special form of the electro-magnetically actuated pawl mentioned above in this way that when turning this operating member in the direction opposite to the closing movement the carrier engages an abutment formed on the pawl, lifts it and so allows the bridging member being thrown out independently of the coupling.

A fifth feature is a special position of the

electro-magnetically- or hand actuated pawl according to the fourth feature so that same is fixed to the coupling body in such manner that the abutment is situated next to one of the stops, with the carrier of the operating member reaching between the nose on the pawl and the stop so that the carrier has always the same relative position to the pawl, a constant, little amount of backward movement of the operating member being necessary to throw the switch out, while at the same time the back lash of the carrier is small.

A maximum cut-out switch according to this invention may advantageously replace the known current limiting apparatus as for instance the well known types with mercury contacts.

A constructional form of a switch embodying the invention is illustrated on the accompanying drawings; it must, however, be understood that rotary maximum cut-out switches only showing the features of the invention in part are without the scope of the invention.

Figure 1 is a vertical section on the center line of the device.

Fig. 2 is a sectional view on the line A A of Fig. 1 looking in the direction of the arrows.

Fig. 3 is a similar sectional view on the broken line B B of Fig. 1.

Fig. 4 is a top view of the terminal board looking from the line C C of Fig. 1 in the direction of the arrows.

Fig. 5 is an inside view of the bottom of the casing.

Figs. 6 and 7 are a side and a top view respectively of a protecting cover which may be sealed.

Fig. 8 is a top view of the base plate upon which the maximum cut-out is mounted.

Fig. 9 is a cross section on the line D D of Fig. 8.

The bottom 1 of the casing is provided with three upwardly projecting posts 2 to which the feet 5 of the supporting plate 3 for the coil 4 are fixed. These parts are preferably made of iron in order that they

may be included in the magnetic circuit. Within the coil 4 the rotatable iron core 6 is arranged. The upper part of this core projects from the coil and is provided with an abutment or nose 7. On the coil a plate 8 with a vertical edge is secured, in which plate a disk 9 freely rotatable around the core 6 is mounted.

The plate 8 and the disk 9 as well as the supporting plate 3 are slotted in order to avoid eddy-currents as much as possible. The disk 9 may be rotated by hand by means of the operating member 10 and the drivers 11 engaging the stops 12 stamped out of and projecting upwardly from the disk 9. On the disk 9 the brass pawl 15 is slidably mounted in guides 13 and

14. This pawl is provided with a nose 16 adapted to catch under the influence of the spring 17 into the recess adjacent to the abutment 7 of the core 6. The pawl 15 carries the armature 18; in order to make the switch adapted to cut out at different intensities of current the distance between the armature 18 and the core 6 is made adjustable.

Upon the rotatable disk 9 a spring 19 is further fastened, said spring engaging a recess 20 in the vertical edge of the plate 8. At its lower extremity and projecting from the coil 4 the core 6 carries the bridging member, consisting of an insulating bushing 21 in which the bridging contact consisting of contact strips 22 connected to each other by means of a ring plate 23 free so as to form a bridging member from the core are embedded. Around the insulating bushing 21 the insulating ring 23 carrying the terminals 24, 25 of the coil and the contact springs 26, 27 is placed. The ring 23 is fixed by means of screws 28 to which a seal may be attached. These screws connect the protecting cover 30, the supporting plate 3 and the bottom plate 1 by means of the posts 2 and the feet 5. Of a spiral spring 31 one end is connected with the core 6 and the other with the supporting plate 3. A disk 32, provided with a projection 33 on its circumference, is attached to the core 6.

The rotation of the core 6 by means of the disk 32 is limited in both directions by stops 34, 35 stamped and bent downwardly from the supporting plate 3. The magnetic field passes chiefly through the armature 18 by providing an iron strip 36 fixed to the supporting plate 3 and reaching with its free upper end next to the armature. The arrangement is, however, such that a sufficient stray field remains in order to make the core adapted to act as a magnetic blow-out.

To the bottom plate a terminal box 37 is fixed in which the insulating block 38 with the usual terminal screws is placed. This terminal box is protected by the cover 40 which is sealed through the lips 41 after the switch has been connected up.

Before the connections are made, the base plate 42 is secured to the switchboard or the like. The base plate is provided with a dove-tailed projection 43 adapted to engage an opening 44 in the bottom plate.

After the switch has been placed upon the base plate with the projection 43 reaching through the opening 44 it is turned about 90° and connected up, whereupon the removal of the switch by unauthorized persons is prevented by the seal fastened to the lips 41. On account of the screws 28 being sealed as well the mechanism is inaccessible to the man charged with installing the switch. An insulating plate 45 covers the opening 44 during transport.

The maximum cut-out now operates as follows:

In the drawing the normal "out" position is illustrated. When switching in the operating member 10 is turned in a clockwise direction, whereby the drivers 11 moves the disk 9 with the pawl mounted thereupon, the spring 19 thereby sliding along the inside of the vertical edge of the plate 8, while the nose 16 slides over the circumference of the core 6.

After the operating member has been turned about 270° the nose engages the abutment 7 and during the further rotation of the operating member in the clockwise direction the core 6 is caused to follow this movement, thereby tensioning the spring 31. After the operating member 10 has been rotated 360° the spring 19 engages the opening 20, while further movement is prevented by the stop 35 and the projection 33. In releasing the operating member 10 the spring 19 prevents the return movement of the coupling and the bridging member under the influence of the spring 31. As soon as the armature 18 is attracted the nose 16 no longer prevents the return movement of the core and by the action of the spring 31 the bridging member is thrown out. In order to switch out by hand the operating member is slightly turned in a counter-clockwise direction, until the carrier engages the edge 29 of the pawl 15 and pushes the latter out of engagement with the abutment 7.

Having now described our invention, what we claim as new and desire to secure by Letters Patent is:

1. In an electric maximum cut-out switch, an operating member, a loose member, means whereby said operating member drives said loose member when closing the switch, a contact-carrying member, means whereby a disengageable connection is formed between the loose member and the contact-carrying member when the operating member is moved to close the switch, and means whereby the operating member may disengage said connection.

2. In an electric maximum cut-out switch, an operating member, a loose member, means whereby said operating member drives said loose member in one direction only when closing the switch, a contact-carrying member, means whereby a disengageable connection is formed between the loose member and the contact-carrying member when the operating member is moved to close the switch, means for holding the loose member in a fixed position when the switch is closed, and means whereby the operating member may disengage said connection leaving the loose member in said position.

3. In an electric maximum cut-out switch, a bridging member, a central spindle adapted to actuate said bridging member, a loose

member co-axially arranged on said spindle, an abutment projecting outwardly from said central spindle, an electromagnetically operated pawl mounted on said loose member and having an inwardly projecting portion adapted to engage said abutment when the loose member is rotated, an operating member adapted to drive said loose member in a forward direction, and a pawl arresting the loose member when it reaches the "switched-in" position.

4. In an electric maximum cut-out switch, a bridging member, a central spindle adapted to actuate said bridging member, a loose member co-axially arranged on said spindle, an abutment projecting outwardly from said central spindle, a non-magnetic pawl mounted on said loose member and having an inwardly projecting portion adapted to engage said abutment when the loose member is rotated, a paramagnetic armature adjustable on said pawl, an operating member adapted to drive said loose member in a forward direction, and a pawl arresting the loose member when it reaches the "switched-in" position.

5. In an electric maximum cut-out switch, a bridging member, a central spindle adapted to actuate said bridging member, and formed of paramagnetic material, an electromagnet coil surrounding said spindle so that the latter is traversed by the magnetic field, a loose member co-axially arranged on said spindle, an abutment projecting outwardly from said central spindle, a non-magnetic pawl mounted on said loose member and having an inwardly projecting portion adapted to engage said abutment when the loose member is rotated, a paramagnetic armature on said pawl, an operating member adapted to drive said loose member in a forward direction, and a pawl mounted on said loose member to arrest it when it reaches the "switched-in" position.

6. In an electric maximum cut-out switch, an operating member, a spindle carrying a bridging member, a loose member between said operating member and the spindle of the bridging member, an electro-magnetically-influenced releasing pawl on said loose member engaging said spindle in the forward direction only, a loose coupling between said loose member and said operating member adapted to engage said loose member when moved in the forward direction 115 and to engage and lift said releasing pawl when moved in the backward direction.

7. In an electric maximum-cut-out-switch, an operating member, a spindle carrying a bridging member, a loose member between 125 said operating member and the spindle of the bridging member, an electro-magnetically-influenced releasing pawl on said loose member engaging said spindle in the forward direction only, stops on said loose 130

- member, a driver connected to said operating member adapted to engage said stops when moved in the forward direction, said driver being further adapted to engage and lift said releasing pawl, when moved in the backward direction.
8. In an electric maximum cut-out switch, the combination of an operating member, a rotatable bridging member carried by but 10 insulated from its spindle, stationary contact members adapted to be engaged by said bridging member on rotation of said spindle, an abutment on said spindle, a disk loose from said spindle and said operating member, a releasing pawl of non-magnetic material on said disk engaging said abutment on said spindle, a paramagnetic armature adjustably connected to said pawl, an electric coil around said spindle, paramagnetic strips outside said coil conducting the magnetic flux induced by said coil from one end of said spindle to the opposite end, said strips being so dimensioned and arranged that a sufficient stray field passes between the contacts of said bridging member when 15 being switched out, stops on said disk, a driver connected to the operating member engaging said stops when being turned in the forward direction and lifting said releasing pawl when being turned in the backward direction, a spring pawl on said loose disk co-acting with a fixed member to prevent rotation of said disk in the backward direction when the switch has been closed, a spring acting on said spindle and opposing the "switching in" movement of said bridging member and fixed stops co-acting with 20 said bridging member for limiting a rotat- 25 ing movement in both directions.
9. In an electric maximum cut-out switch the combination of an operating member, a rotatable bridging member carried by but 30 insulated from its spindle, stationary contact members adapted to be engaged by said

bridging member on rotation of said spindle, an abutment on said spindle, a disk loose from said spindle and said operating member, a releasing pawl of non-magnetic material on said disk engaging said abutment on said spindle, a paramagnetic armature adjustably connected to said pawl, an electric coil around said spindle, paramagnetic strips outside said coil conducting the magnetic flux induced by said coil from one end of said spindle to the opposite end, said strips being so dimensioned and arranged that a sufficient stray field passes between the contacts of said bridging member when 35 being switched out, stops on said disk, a driver connected to the operating member engaging said stops when being turned in the forward direction and lifting said releasing pawl when being turned in the backward direction, a spring pawl on said loose disk co-acting with a fixed member to prevent rotation of said disk in the backward direction when the switch has been closed, a spring acting on said spindle and opposing the "switching in" movement of said bridging member, and fixed stops co-acting with 40 said bridging member for limiting a rotat- 45 ing movement in both directions.

In testimony whereof we have signed our 45 names to this specification in the presence of two subscribing witnesses.
